UNITED STATES PATENT OFFICE.

FREDERIC W. ERICKSON, OF LARCHMONT, NEW YORK.

NIGHT AND DAY STADIUM.

Application filed July 21, 1927. Serial No. 207,368.

This invention relates to structures quite commonly known as stadiums which are large enclosed areas used for the playing of base ball and other games, and frequently employed for other exhibitions.

Base ball is a very fast game. The central object of interest is a ball of such small diameter that it must be handled by the players in a strong light not only to enable the players themselves to see and keep track of it, but also that the spectators may follow the play even from the most distant points in the stadium.

The principal object of the invention is to provide an exhibition structure which will enable the owners to operate it for profit at times when weather conditions or darkness would not permit the use of the usual stadium. Moreover, after a heavy rain the playing field of the ordinary stadium is in such condition that games frequently have to be postponed. With my improved structure, nothing but an exceedingly violent storm can prevent the use of the stadium either in day or night times. Upon the approach of any such storm the canopy protection can be lowered and stowed to avoid damage such as ripping of the canvas sections.

Of course another object which is attained by my invention is avoidance of the disappointment to the public when deprived of seeing a game that has been planned for, and the convenience to the public in being able to attend night games.

With these objects in view, my invention consists in the construction and combination of parts substantially as hereinafter described and claimed.

Of the accompanying drawings:—

Figure 1 is plan view of the field and seats and surrounding towers, but omitting the canopy sections.

Figures 2 and 3 represent sections on lines

45 2—2 and 3—3 respectively of Figure 1 and including the canopy structure.

Figure 4 is a detail cross sectional view illustrating the relationship of the canvas canopy strips and their aprons.

50 Figure 5 is a detail view illustrating the relationship of the main cables, messenger cables, and canopy.

Figure 6 is a plan view of a portion of one of the canopy strips shown in Figure 4.

55 Figure 7 represents a section on line 7—7 of Figure 6.

Similar reference characters designate similar parts or features in all of the views.

So far as the playing field and the seating arrangements are concerned, they may be of any well-known or preferred type. As illustrated in the accompanying drawings, the field 12 is surrounded by a wall or fence 13. The bleacher seats are indicated at 14 (Figs. 1 and 2) and lower grand stand seats 15, 16, the latter being protected by a roofing 17 supported by slender posts or columns 18 (Figs. 1, 2 and 3).

Rising from the ground at opposite sides of the field and seats, and preferably also at one or both ends thereof, are towers or columns 19 connected by diagonal braces 20 (Fig. 2) and preferably having suitable guys 21 (Fig. 3) and pennant or flag poles 22. Said towers are of such height (approximately 200 feet) and are sufficiently numerous to support the canopy strips and their manipulating gear which will now be described.

At the top of each of the side towers is a pulley 23 (Fig. 5) over which a main cable 24 runs from a suitable windlass not necessary to illustrate, as such hoisting gears may be of any preferred type, usually motor-operated. The two main cables of each pair approach each other from two opposite towers and are joined to a cable link by shackles 26, all of said cable links 25 with their shackles, when the canopy gear is in use, being in position side by side and so as to form a peak row along and over substantially the mid-width of the field or arena.

In each shackle 26 is mounted a pulley 27 for a purpose presently described, and each shackle has secured to it one end of a cable 28 hereinafter referred to as a messenger cable, which cable passes over a pulley 29 mounted in bearings near the top of a tower 19, and extends down to another windlass not necessary to illustrate.

The canopy sections are shiftable along the messenger cables to meet all conditions of either complete protection from rain or such partial protection as when direct sun rays are not wanted on portions of the field or seats. To this end, the canopy comprises strips or sheets 30 of canvas or other suitable flexible and protecting material, said strips having cross braces 31 which may be curved from end to end. To opposite ends of the alternate braces 31 are suitably connected trolleys 32 (Figs. 4 and 6) running

on the messenger cables 28. One edge of each strip 30 has depending aprons 33, each apron having a gravity rod 34 enclosed in its lower edge (Fig. 4), the purpose of the 5 aprons being explained hereinafter. The structure is such that the long strips of canvas 30, with their aprons 33, can be extended as indicated in the right hand portion of Figure 5, or withdrawn and folded in loop 10 condition as indicated in the left hand portion of said Figure, in which portion illustration of the aprons is omitted to avoid confusion.

One end of each extensible and collapsible 15 canopy section is secured to a tower 19 as at 37 (Fig. 5) while the trolley 32 at the other end of said section has a cable 38 secured to it, said cable passing around pulley 27 in a shackle 26 and then back over a pulley 20 39 mounted in bearings near the top of a tower 19 and down to position where, by a windlass or manual operation, said cable can be used to extend the canopy section toward or up to the peak of the structure 25 where the shackles 26 are positioned, or can be released so that the trolleys will travel down the inclined messenger cables and carry the canvas section to folded or collapsed condition at the side of the arena.

30 When in use during rainy weather, and also usually for evening or night games or entertainments, the canopy strips 30 are hoisted to as nearly a taut condition as possible; in fact more taut than illustrated in 35 the right hand portion of Figure 5. The canvas sags sufficiently between the edges to form valleys for conducting rain to the sides of the arena. Such sagging may be aided by properly curving the cross braces 31. 40 The canopy sections can be so drawn toward the peak that those on one side will overlap the higher ends of those on the other side at the mid-width of the roof, to prevent a driving rain storm from effecting any precipitation through any peak openings. If 45 the wind is blowing in the direction of the arrow *a* (Fig. 5) the right-hand canopy sections are first drawn up taut and then the left-hand canopy sections are drawn up until 50 their upper ends extend under and somewhat beyond the upper ends of the sections which were first pulled up. If the wind is blowing in the direction of the arrow *b* in said Figure 5, the order of pulling up the right and left hand canopy sections will be 55 reversed. If the wind blows in any such direction as would tend to drive rain in the direction of the arrows *c* (Fig. 4) the aprons 33, with their edge weight rods 34 will prevent 60 the passage of rain between the overlapping side margins of the sections. As illustrated by Figure 4, the messenger cables 28 are arranged in two levels in order to support the canopy sections to attain the objects just mentioned. And as also illustrat-

ed by said Figure 4, each strip section 30 is of such width relatively to the distance between its two supporting messenger cables (one of which is at a lower level than the other) that said section sags so as to provide 70 a valley or trough for conducting rain water away to the side of the arena.

In practice, especially for ball games, the overlapping of the sides or edges of the canvas sections is such that each long section 75 has that margin which is farthest from the home plate extending partly under the next farther section so that a ball, illustrated at A in Figure 4 and travelling in the direction of arrow *d* as the result of the batsman 80 knocking it to the far field, will not, if it strikes the canvas, be pocketed in a canopy valley.

Preferably side curtains are also employed as indicated at 40 in Figures 2 and 85 3, which curtains may be hung in any suitable way but preferably so that they may be raised or lowered according to the weather or other conditions. Therefore said curtains are indicated as suspended from rollers 90 41.

Mounted in suitable locations, but preferably well up on the inner sides of the towers 19, are search or flood lights 42 all of which, as best illustrated in Figure 5, are so positioned that no rays therefrom are directed either on the field or the seats for the audience. The rays are directed against the roof canopy and the side curtains all of which are, preferably, painted white or a very light 100 color which will provide reflecting surfaces capable of satisfactorily illuminating the entire arena, so that the players in action, and even a base ball in its travel about or over the field, can be readily distinguished 105 by all within the arena. The side curtains aid in effecting this result or object, and they also provide suitable space for advertising, the value of which to the owners is considerable. 110

If for any reason, such as the approach of a very violent storm, it is desired to quickly clear the space overhead from all canopies and cables, it is only necessary to release the cables and permit their overhead ends and the shackles 26 to reach the ground. Then the pins which secure the cables 24 and 28, and the links 25, to the shackles are removed, after which the parts may be stowed quite compactly. The reverse of this 115 dis-mounting operation enables the parts to be restored or re-erected without much loss of time. 120

It will now be understood that the invention provides for a complete canvas roof 125 made up of sections of fabric, so constructed and mounted as to be easily and quickly put in place or removed. Ordinary breezes may circulate through the entire structure with facility and without noise, with results far 130

preferable, in hot summer weather, to what players and audiences must experience in permanently closed structures.

Important advantages obtained by the structure which I have described, are the following:—

When a base ball game can not be played on an open field, because of the weather, that game is postponed and is usually played at some later date when two games are played for one admission. While this may bring a little added revenue, that is, a little more than a single game would bring, it is much less than the admission fees for two games.

Owing to the fact that the use of my improved stadium can be counted on with certainty, day or night, and regardless of weather, with very rare stormy exceptions, it is possible for it to be employed for band concerts, prize fights or boxing contests, conventions, mass meetings etc., thereby adding materially to the income of the owners and the pleasure of the public.

At times on hot summer days when the sunlight interferes with the best playing on the field, or it is too hot for the comfort of the spectators, such portions of the canopy and side curtains can be pulled into place as may be desired to act as a sun shade for more or less of the interior.

It is a well known fact that band concerts and singing in the open air are not very successful unless backed by some kind of sounding board to project the sound waves. On account of the flexibility of the canopy sections and curtains of my improved stadium, the effectiveness of the concerts or the transmission of the human voice is not reduced by echoes.

Having now described my invention, I claim:—

1. A roof canopy comprising a plurality of flexible strips, and supporting cables in

two levels for said strips, each strip having one edge connected to a lower cable and the other edge connected to an upper cable.

2. A roof canopy comprising a plurality of flexible strips, and supporting cables in two levels for said strips, each strip having one edge connected to a lower cable and the other edge connected to an upper cable, said strips having depending aprons adjacent to their higher edges.

3. A roof canopy comprising a plurality of flexible strips, and means for supporting each strip in inclined trough-shaped condition to conduct rain water.

4. A structure for use with a field for games and other events, said structure having overhead supporting cables, inclined messenger cables supported by the overhead cables at an intermediate point of the latter, and roof canopy material supported by and shiftable along said messenger cables.

5. A structure for use with a field for games and other events, said structure having overhead supporting cables, messenger cables connected with said overhead cables, and flexible canopy sections provided with depending aprons and having trolleys mounted on said messenger cables.

6. A structure for use with a field for games and other events, said structure having a series of tall towers surrounding the field, main cables crossing the field and supported by said towers, inclined messenger cables supported by the main cables at an intermediate point of the latter, flexible canopy sections provided with depending weighted aprons and having trolleys mounted on said messenger cables, and means for shifting said canopy sections along said messenger cables.

In testimony whereof I have affixed my signature.

FREDERIC W. ERICKSON.
